US00D648747S

(12) **United States Design Patent**
McCombs et al.

(10) **Patent No.:** US D648,747 S
(45) **Date of Patent:** ** Nov. 15, 2011

(54) **COMPRESSOR END CAP**

(75) Inventors: **Norman R. McCombs**, Tonawanda, NY (US); **Robert Bosinski**, West Seneca, NY (US); **Michael R. Valvo**, East Aurora, NY (US)

(73) Assignee: **AirSep Corporation**, Buffalo, NY (US)(**) Term: **14 Years**(21) Appl. No.: **29/361,599**(22) Filed: **May 13, 2010**(51) LOC (9) Cl. ..... **15-02**(52) U.S. Cl. **D15/9**

(58) **Field of Classification Search** D15/7-9; D23/231, 232, 225; 417/60, 235, 265, 321, 417/355, 358, 363, 359, 410.1, 415-416, 417/405, 900; 60/408, 412; 184/26-37; 415/140-147; 123/495, 509
